UNITED STATES PATENT OFFICE

SAMUEL COHN, OF NEW YORK, N. Y.

APPARATUS FOR CRIMPING AND GATHERING THE ENDS OF TUBULAR FABRICS.

No. 887,990.

Specification of Letters Patent.

Patented May 10, 1908.

Application filed August 19, 1907. Serial No. 309,178.

To all whom it may concern:

Be it known that I, SAMUEL COHN, a citizen of the United States of America, residing at New York, N. Y., in the United States of America, have invented certain new and useful Improvements in Apparatus for Crimping and Gathering the Ends of Tubular Fabrics, of which the following is a specification.

This invention relates to improvements in machines, such for example as described in the specifications of my former Letters Patent, Nos. 678542 and 798090 for crimping or folding the ends of tubular textile fabric, for example, the heads of mantles for incandescent gas lighting and for drawing a binding or shirring thread into the crimped or folded part of such fabric.

In the accompanying drawing Figure 1 shows a machine provided with my improvements in side elevation. Figs. 2 and 3 show the threading device for the drawing-in needles in two positions. Fig. 4 shows a special form of the threading device. Fig. 5 shows the crimping or folding device in end elevation. Figs. 6 and 7 show the crimping or folding device in plan in two positions. Fig. 8 is a plan view of the entire machine shown in Fig. 1; Fig. 9 is a view similar to Fig. 5 with the parts in a different position; and Figs. 10 and 11 are perspective views showing in detail the inner and outer jaw members.

a is the frame of the machine, on which are mounted two standards b and c, in which the driving shaft d is mounted and can be turned by means of a lever e. On the shaft d is mounted a bevel wheel f, the teeth of which are partly cut away and which gears with a correspondingly shaped bevel-wheel g mounted at the side of the shaft. The wheel g, by means of a fork h, reciprocates on guide-rods k a carriage j bearing the drawing-in needles i, i. On the shaft d are also mounted two disks l, l provided with cam-grooves, which produce the inward and outward motion of the outer crimping or folding jaws m, m, and a cam-disk n moving the hooks o, o which serve to insert the binding or gathering thread into the drawing-in needles i, i.

z, z' are the inner jaws which are adapted to enter and fold the material (shown by dotted lines in Figs. 6 and 7). The groups of inner jaws z, z' and the outer jaws m, m

are pivotally mounted on a common pin 1, and each of these groups z, z' and m, m is provided with a lever 3, 3 and 2, 2 respectively, these levers being connected in pairs z, m and z', m by pins 4 and 5, respectively, the ends of these pins 4 and 5 sliding in the cam grooves in the disks l. As the disks l turn, the groups of jaws z, z' and m, m are moved together about the pin 1, the group z, m which is connected by the pin 4 turning to the left, while the group z', m' which the pin 5 connects, simultaneously move to the right (see the arrows in Fig. 5), so that the position indicated in Fig. 9 is reached.

In order to permit a relative movement of the inner jaw members, as well as the outer members, the jaws of the outer members are arranged in staggered or zig-zag relation, and the inner jaws are arranged in sets, the alternate jaws being connected to move simultaneously in opposite directions and enter the recesses formed between the outer jaws, and thus when the jaws are in crimping or folding position, the inner jaws, as well as the outer ones, will be arranged in staggered or zig-zag relation, as shown in Fig. 7.

By mounting the jaws of the inner folding members for movement relatively to each other, as well as with respect to the jaws of the outer folding members, the inner jaws will be arranged in alignment, as shown in plan view Fig. 8, when the mantle or other tubular body is applied over them, and consequently, the mantle may be applied with facility by reason of the compact arrangement of these inner jaws which enter the tubular body, and moreover, a greater depth of indentation or crimp is obtainable without unduly enlarging the size of the jaws. During the gathering or crimping action, these inner jaws move toward and meet the approaching outer jaw members m, and while the crimp or indentation produced is relatively deep, the simultaneous movement of the inner and outer cooperating jaws effect the crimping action without increasing the period of time elapsing in performing this part of the cycle of operations.

At their front ends the needles i, i are guided in a carriage p which can slide to and fro on the rods k. On the carriage p is fixed a central rod q which is guided in the carriage j and on which pressure is exerted by

means or a spiral spring *r* through an adjusting screw *s*, and consequently, since it is held by friction, it takes part in the movements of the carriage *j*.

5 The hooks *o*, *o* are both secured to a lever *w* which, by means of a slide *u*, can be oscillated by the cam *n* on the shaft *d*, in order to insert the hooks *o*, *o* into the eyes of the needles, the lever *w* being provided with a 10 slot in the present instance to receive a pin *v* on the slide *u*, whereby reciprocation of the latter serves to automatically move the thread engaging hooks to and from operative position. In order to enable the two hooks 15 to enter at the same time into the eyes of the needles, for the purpose of engaging the ends of the gathering or shirring thread, either the upper hook *o* is suitably bent (Figs. 2 and 3) or the eyes of the needles are made 20 sufficiently large to enable the two hooks to pass through the eye of the front needle (Fig. 4).

The separate parts *z*, *z'* of the middle member of the folding device operate with the 25 actuating levers of the outer folding jaws *m*, *m* in the manner herein described so that, during the inward motion of these jaws of the outer folding member, the jaws *z*, *z'* of the inner folding members are simultaneously moved outwards in opposite directions, so that the relatively displaced teeth of the outer crimping or folding jaws enter the spaces and fold the material (shown dotted in Figs. 6 and 7). By this means, the pins 30 8 (see Figs. 5 and 6) on the parts *z*, *z'* at the same time serve to support the tubular fabric when applied over the inner jaws. If desired, the parts *z*, *z'* can be fixed in their 35 drawn out positions (Fig. 7), so that only 40 the outer crimping or folding jaws *m*, *m* require to be moved, the parts *z*, *z'* in this instance being supported rigidly in staggered or zig-zag relation corresponding to the 45 position occupied during the crimping or folding operation by these parts or inner jaws when movable.

1. An apparatus for crimping or folding the ends of tubular textile fabric and for drawing a gathering or shirring thread into the crimped or folded part of said fabric, said 50 machine comprising means for supporting and crimping said fabric, needles, a movable carriage for said needles, means for moving said carriage, thread-carrying hooks adapted to enter the eyes of said needles, a single carriage bearing both of said hooks and means for moving said carriage transversely to said needles.

2. An apparatus for crimping or folding 60 the ends of tubular textile fabric and for drawing a gathering or shirring thread into the crimped or folded part of said fabric, said machine comprising means for supporting and crimping said fabric, needles, a movable

carriage for said needles, means for moving 65 said carriage, thread-carrying hooks adapted to enter the eyes of said needles, a lever bearing both of said hooks, and means for oscillating said lever so as to move said hooks into and out of the eyes of said needles, substantially as described.

3. An apparatus for crimping or folding the ends of tubular textile fabric and for drawing a gathering or shirring thread into the crimped or folded part of said fabric, said 75 machine comprising bars adapted to stand in a zigzag series and capable of receiving said tubular fabric, outer crimping or folding jaws, teeth on said jaws for coacting with said zigzag series of bars, means for moving 80 said outer jaws towards and away from said bars, and means for passing a binding or shirring thread through the crimped or folded part of said fabric.

4. An apparatus for crimping or folding 85 the ends of tubular textile fabric and for drawing a gathering or shirring thread into the crimped or folded part of said fabric, said machine comprising a series of bars adapted to be arranged in alinement for receiving said 90 tubular fabric, means for moving said bars relatively to each other so as to form a zigzag series, outer crimping or folding jaws, teeth on said jaws for coacting with said zigzag series of bars, means for moving said outer 95 jaws towards and away from said bars, and means for passing a binding or shirring thread through the crimped or folded part of said fabric.

5. An apparatus for crimping or folding 100 the ends of tubular textile fabric and for drawing a binding or shirring thread through the crimped or folded part of said fabric, said apparatus comprising bars for receiving said tubular fabric, transverse pins on said bars 105 for supporting said tubular fabric, means for moving said bars from a straight to a zigzag series and vice versa, outer toothed jaws for coacting with said bars when the latter are in a zigzag series, means for moving said jaws 110 towards and away from said bars, needles, a carriage bearing said needles, means for reciprocating said carriage, hooks for inserting a thread into the eyes of said needles, and means for moving said hooks transversely to 115 said needles.

6. An apparatus of the class described, comprising a row of inner jaws, the alternate jaws being connected in sets, outer jaws mounted to coöperate with the inner jaws, 120 and means for arranging the inner jaws substantially in alinement to receive a tubular body over them and for moving the sets of inner jaws simultaneously in opposite directions to arrange them in staggered relation. 125

7. An apparatus of the class described, comprising a row of inner jaws adapted to occupy a staggered relation, and a pair of

outer jaw members having the jaws thereon arranged in staggered relation with respect to the jaws of each jaw member and to the coöoperating inner jaws, the outer jaws being movable into and out of coöperative relation with the respective inner jaws.

In testimony whereof I have hereunto set

my hand in presence of two subscribing witnesses.

SAMUEL COHN.
